UNITED STATES PATENT OFFICE.

HARLEY T. PECK, OF LEBANON, OHIO, ASSIGNOR TO THE PETERS CARTRIDGE COMPANY, OF CINCINNATI, OHIO, A CORPORATION OF OHIO.

PRIMER FOR SMALL-ARMS AMMUNITION.

1,416,121.

Specification of Letters Patent. Patented May 16, 1922.

Application filed July 20, 1921. Serial No. 486,223.

No Drawing.

To all whom it may concern:

Be it known that I, HARLEY T. PECK, a citizen of the United States, residing at Lebanon, in the county of Warren and State of Ohio, have invented certain new and useful Improvements in Primers for Small-Arms Ammunition, of which the following is a specification.

This invention relates to a priming composition for ammunition and has for its object the provision of a substance of the class named which shall be of improved composition and efficiency.

The invention is exemplified in the composition of material described in the following specification, and it is more particularly pointed out in the appended claims.

A priming composition made according to the present invention has pronounced qualities of sensitiveness, freedom from fouling in the barrel of the fire-arm, improved qualities of ignition with propellants, and increased uniformity of all ballistic qualities. It will function in a more uniform manner than priming compositions heretofore known and is more independent of variations which may exist within the primer or cartridge in which it is used.

In a center-fire or rim-fire primer made according to one embodiment of the present invention the combination of substances used to produce a primer of improved sensitiveness contains a sulpho-cyanate, tri-nitro-resorcinol, an oxidizing agent and normal lead tri-nitro-resorcinol. When these substances are mixed together there is a slight but complicated chemical reaction which I consider responsible for the improved properties described above. The following proportions are given by way of example of a composition containing these substances:

5% by weight of tri-nitro-resorcinol.

5% by weight of lead sulpho-cyanate.

40% by weight of normal lead tri-nitro-

resorcinol.

50% by weight of potassium chlorate.

The proportions of the materials may be varied to meet different requirements. For some purposes the following proportions may be used:

15% by weight of tri-nitro-resorcinol.

20% by weight of lead sulpho-cyanate.

15% by weight of normal lead tri-nitro-resorcinol.

55 50% by weight of potassium chlorate.

For some cartridges where a lesser force and heat of explosion is required, I may use the composition of tri-nitro-resorcinol, a sulpho-cyanate and an oxidizing agent. For certain purposes and with certain propellant 60 powders, these three substances are in themselves, when of satisfactory purity and properly mixed, a suitable priming composition. One example of such a composition is given below:

16% tri-nitro-resorcinol.

32% lead sulpho-cyanate.

52% potassium chlorate.

Rim-fire cartridges in general require a somewhat different type of composition 70 from center-fire, and for such cartridges an abrasive substance, such as ground glass, emery or ferro-silicon may be added to the composition. A suitable composition for rim-fire cartridges may contain:

30% normal lead tri-nitro-resorcinol.

10% lead sulpho-cyanate.

10% tri-nitro-resorcinol.

20% potassium chlorate.

30% ground glass.

Instead of a sulpho-cyanate I may use another fuel such as antimony sulphide.

In place of lead sulpho-cyanate some other suitable cyanate, such as copper sul-

pho-cyanate may be substituted.

Instead of potassium chlorate another oxidizing agent such as potassium perchlorate, barium nitrate, barium peroxide or other oxidizing substances, may be used.

Instead of normal lead tri-nitro-resorcinol 90 other suitable detonating explosives, such as di-plumbic di-tri-nitro resorcinol, one of the organic diazo compounds or mercury fulminate, or some detonating nitro compound, such as tri-nitro tolene, tri-nitro nitro-95 anilid or tri-nitro methyl nitro-anilid may be used.

The priming compositions of the present invention may be mixed and introduced into the primer cup or rim-fire shell in the usual 100 manners well known to those skilled in the art.

I claim:

1. A priming composition containing tri-nitro-resorcinol, a sulpho-cyanate, an oxidiz- 105 ing agent and a detonating explosive.

2. A priming composition containing tri-nitro-resorcinol, a sulpho-cyanate, an oxidiz- 110 ing agent and normal lead tri-nitro-resorcinol.

3. A priming composition containing tri-nitro-resorcinol, lead sulpho-cyanate, an oxidizing agent and normal lead tri-nitro-resorcinol.
5. A priming composition containing tri-nitro-resorcinol, a sulpho-cyanate, potassium chlorate and normal lead tri-nitro-resorcinol.
5. A priming composition containing tri-nitro-resorcinol, lead sulpho-cyanate, potassium chlorate and normal lead tri-nitro-resorcinol.
10. A priming composition containing tri-nitro-resorcinol, lead sulpho-cyanate, potassium chlorate, normal lead tri-nitro-resorcinol and an abrasive substance. ¹⁵
7. A priming composition containing tri-nitro-resorcinol, a sulpho-cyanate and an oxidizing agent.
8. A priming composition containing tri-nitro-resorcinol, lead sulpho-cyanate, and 20 potassium chlorate.

In testimony whereof I have signed my name to this specification on this fifth day of July, A. D. 1921.

HARLEY T. PECK.
